(57) **CLAIM**

The ornamental design for sport training device, as shown and described.

DESCRIPTION

FIG. 1 is a top plan view of a sport training device in an open configuration showing our new design, with environment depicted in dashed lines and being no part of the claimed design;

FIG. 2 is a bottom plan view of the invention shown in FIG. 1, with environment depicted in dashed lines and being no part of the claimed design;

FIG. 3 is a front elevation view of the invention shown in FIG. 1, with environment depicted in dashed lines and being no part of the claimed design;

FIG. 4 is a rear elevation view of the invention shown in FIG. 3, with environment depicted in dashed lines and being no part of the claimed design;

FIG. 5 is a front perspective view of the invention shown in FIG. 1, with environment depicted in dashed lines and being no part of the claimed design;

FIG. 6 is a rear perspective view of the invention shown in FIG. 5, with environment depicted in dashed lines and being no part of the claimed design;

FIG. 7 is a perspective view of the invention shown in FIG. 1 in a closed configuration, with environment depicted in dashed lines and being no part of the claimed design; and, FIG. 8 is a side view of the invention shown in FIG. 7 in a closed configuration, with environment depicted in dashed lines and being no part of the claimed design.
